C. M. YODER.
BENDING MACHINE.

APPLICATION FILED DEC. 17, 1910. RENEWED OCT. 30, 1916.

1,264,248.

Patented Apr. 30, 1918.

UNITED STATES PATENT OFFICE.

CARL M. YODER, OF CLEVELAND, OHIO.

BENDING-MACHINE.

1,264,248.

Specification of Letters Patent. Patented Apr. 30, 1918.

Application filed December 17, 1910, Serial No. 597,769. Renewed October 30, 1916. Serial No. 128,632.

To all whom it may concern:

Be it known that I, CARL M. YODER, a citizen of the United States, and resident of Cleveland, in the county of Cuyahoga and State of Ohio, have invented certain new and useful Improvements in Bending-Machines, of which I hereby declare the following to be a full, clear, and exact description, such as will enable others skilled in the art 10 to which it appertains to make and use the same.

This invention relates to apparatus for bending rods, bars, sheet metal strips or bands and other articles into any desired 15 shape. The invention is especially adaptable for bending a metal plate, strip or band edgewise or in its own plane without in any wise crimping, twisting or deforming the metal.

20 One object of the invention is to provide improved means for bending sections of metal.

Another object of the invention is to provide improved means for fastening and 25 moving either or both ends of the section of metal to be bent.

Another object of the invention is to provide improved means for bending a section of metal and preventing twisting, springing, bulging or crimping thereof while being bent.

30 With these and other objects in view, the invention consists of the parts or combinations of parts hereinafter described and set forth in the appended claims.

As an illustrative application of my invention I have herein disclosed it as adapted for the edgewise bending of a sheet metal strip or band, whereby the strip or 40 band may be used as the mud rim of an automobile wheel guard or fender.

45 For the purpose of illustration I have, in the accompanying drawings, shown and herein described one form of apparatus embodying my invention.

Figure 1 is a plan view of a metal bending apparatus embodying my invention.

Fig. 2 is a side elevation of the apparatus. 50 Fig. 3 is an enlarged transverse section of the supporting and holding means for the metal band, and one of the clamps therefor showing its broadened base resting upon the flat surface of the table; Fig. 4 is an enlarged plan view of one set of gripping

jaws and Figs. 5 and 6 are enlarged end 55 and side views of the same.

In these views 1 is a flat topped table upon which are arranged one or more formers 2, 2. One edge of each former is shaped to give the desired bend, shape or contour 60 to the metal. I preferably provide two formers and correlate them so that the metal strip or band can be bent in opposite directions simultaneously.

3 indicates a series of supports for each former 2. The supports 3 may be arranged along the rear or outer edge of the adjacent former and preferably support it slightly above the table, as shown in Fig. 2, for a purpose to be later set forth. The table is 70 formed with series of spaced openings 4, 4, through which and through the supports 3, 3 bolts or other fastening means 4' can be passed to detachably and adjustably 75 secure the formers to the table in any desired position.

The table 1 is preferably removably secured upon a frame 5 or other suitable support and can be made in one or more sections as desired.

80 6 indicates a trackway arranged at either end of the table 1, and extending transversely thereof. Each trackway 6 is preferably mounted on the support 5 and adapted to movably support a carrier 7 to which one end of the section of metal to be bent is secured. Each carrier 7 may be provided with rollers 8, which run upon a track of the adjacent trackway, and a handle 9, whereby it may be operated. 10 indicates 85 a block slidably mounted on each carrier 7. Each block is formed with an opening 10' to receive wedge shaped gripping jaws 11, between which the adjacent end of the metal band 12 is rigidly secured. The jaws 11 can 90 be clamped and released by a hand lever 13 to which they may be connected by arms 14. Each lever 13 is preferably pivoted upon a bracket carried by the adjacent block 10.

95 The sliding blocks 10 are mounted in guides 15 and the block 10 at one end of the machine is adjustable therein, by means of a yoke 16, attached to a screw rod 17 which engages a wheel nut 18 operating between standards 19 on the carrier.

100 The block 10 at the opposite end of the machine is preferably attached to a T-shaped rod 20 which bears upon compres-

sion springs 21, 21 which in turn press against posts 22, 22 rigidly mounted upon the carriage. When tension is put upon the mud rim, or section of metal to be bent, it will be absorbed by the springs 21 and thus prevent breaking the mud rim.

The mud rim or band 12 may be provided with marginal wires 23, 23, as shown in Fig. 3. The band is preferably prevented from bending in a direction at right angles to its plane by means of two sets of flexible retaining members 24, 25, preferably made of spring steel, and arranged in parallel rows, engaging the opposite faces of the band 12 between their longitudinal edges. These members of each set are secured together by bolts or screws 26, 26 upon which are spacers 27, 27 to maintain the members in alinement. The bolts pass through longitudinal slots 28 thus permitting the flexing of the retaining members 24 and 25, the band 12 being held between them.

The two sets of retaining members are secured against the opposite faces of the band 25 by means of clamping devices preferably arranged on the table at regular intervals. The clamping devices are each formed in two parts viz., a standard 29 which is preferably provided with a broad base 30 extending on both sides of the retaining members and a cam 31 pivoted in the overhanging member 32 at the upper end of the standard 29. The cam is provided with an operating handle 33 and engages a plate 34 which rests upon the upper series of retaining members. A notch 35 in the edge of the cam serves as a stop to prevent the cam from slipping when properly set.

By supporting the formers above the table 40 1, the bases of the standards may slide thereunder during the bending operations. Each base is sufficiently broad to prevent the clamps and band 12 from tilting in any direction under the bending strain, and slides 45 freely upon the smooth surface of the table, but guides in the table therefor can be provided if necessary. The edge of the former or formers is preferably grooved at 36 to admit the wired edge of the band 12 and 50 also assist in keeping the band in one plane while being stretched and bent.

This groove may be of any required shape or depth to correspond to the shape of the projecting edge, and may be formed in any desired manner. In operation, the carriers can be operated separately or simultaneously in conjunction with two curved formers, or if only one curved former is used one carrier can be held immovable while the other is operated to bend the band. Where only one curve is required in the band one carrier at one end of the band 12 is preferably used so that the work can be done more quickly in one operation.

65 When only one carrier is used the other

end of the band or the other carrier can be secured in place by means of a hooked pin 37 in the bed plate or any other suitable means, so that it will not rise when put under tension.

To those skilled in the art of making apparatus of the class described, many alterations in construction and widely differing embodiments and applications of my invention will suggest themselves, without departing from the spirit and scope thereof. My disclosures and the description herein are purely illustrative and are not intended to be in any sense limiting.

Having described the invention what I 80 claim as new and desire to secure by Letters Patent is:

1. In a machine for bending a metal strip, the combination of a support having a curved edge, a curved form on said support having a portion thereof directed toward such edge, strip-anchoring means at one end of said form, and an operating arm adapted to engage the end of a strip which is connected to the anchoring means, said operating arm 90 having a portion adapted to engage the curved edge.

2. In a machine for bending a strip of metal in the direction of its edge, a table, a former thereon provided with a guiding edge adapted to receive the edge of said strip, a securing means for one end of the strip, and a movable securing means for the other end of said strip, one of said securing means being resiliently mounted and a track 100 upon which said movable securing means moves.

3. In a machine for bending a band of metal in the direction of its edge, a table, a former mounted thereon and provided with a forming edge, and with a guiding groove therein, a carriage at one end of the machine, a track therefor, jaws, one of which is movable, mounted in said carriage, and adapted to grip one end of the band, means 105 for gripping the other end of the band, and means for operating said carriage.

4. In a bending machine for a strip of metal, in combination, a table provided with openings, a former thereon having a forming edge, supports for said former adapted to separate the forming edge from said table, means insertible in said openings in said table for securing said former thereto, a track at one end of said table, a carrier adapted to traverse said track, a securing means for one end of said strip of metal in said carrier, and a securing means for the other end of said strip of metal at the opposite end of the machine.

5. In a machine for bending a strip of metal in the direction of its edge, a table, a former thereon, a securing means for one end of the strip, movable securing means for the other end of said strip, one of said 130

securing means being resiliently mounted, and a track upon which said movable securing means moves.

6. In a bending machine for a strip of metal, a table, a former thereon, a carriage, a track therefor at one end of the machine, securing means for one end of the strip in said carriage, securing means for the other end of said strip at the other end of the machine, and removable supports for said metal strip insertible underneath said former and mounted on said table.

7. In a bending machine, a table, a plurality of formers thereon, a track at each end of the table, a carriage movable on each track, a pair of gripping jaws in each carriage, and an adjustable support for one pair of gripping jaws in one carriage.

8. In a bending machine, a table, a plurality of formers thereon, a track at each end of the table, a carriage movable on each track, a pair of gripping jaws yieldingly mounted in one of said carriages, and a pair of jaws adjustably mounted in the other carriage.

9. The combination of a support, a former over which a section of metal may be bent, means for holding and supporting the section of metal, said means including devices which are clamped against the opposite sides of the metal section and prevent distortion thereof, and elements, one of which is movable to bend the section over said former, connected to the opposite ends of the metal section and operating to maintain it under tension while the section of metal is being bent.

10. The combination of a support, a former over which a section of metal may be bent, devices secured to the opposite ends of the section of metal and acting in opposite directions to support the metal section in operative relation to the former, one of said devices being movable on said support, and means engaging the opposite sides of the metal section between said securing devices to prevent distortion or twisting thereof.

11. In a metal bending machine, the combination of a former over which a section of metal is bent, movable devices secured to the opposite ends of the metal section for supporting one longitudinal edge of the metal section in operative relation to the former and co-acting when moved to bend the metal in its own plane thereover, and means extending longitudinally from end to end of the metal section and engaging the opposite faces thereof to prevent its distortion.

12. The combination of a support, a former over which a section of metal may be bent, devices secured to the opposite ends of the section of metal to support one longitudinal edge of the metal section in operative relation to the former, one of said devices being movable in the plane of the metal

section, and means clamped against the opposite faces of the metal section and co-acting to prevent distortion or twisting thereof.

13. In a metal bending machine, the combination of a support, a former over which a section of metal is adapted to be bent, means movably mounted on said support and secured to the opposite ends of the metal section for supporting it in operative relation to the former and bending the metal section thereover, said movable means operating to maintain the metal section taut as it is bent over said former, and means engaging the opposite faces of the metal section to prevent distortion thereof.

14. The combination of a support, a former over which a section of metal may be bent, devices secured to the opposite ends of the section of metal and acting in opposite directions to support the metal section in operative relation to the former, one of said devices being movable, and flexible means clamped against the opposite sides of the metal section and movable therewith to prevent distortion or twisting thereof.

15. The combination of a support, a former over which a section of metal may be bent, devices secured to the opposite ends of the section of metal and acting in opposite directions to support the metal section in operative relation to the former, one of said devices being movable, flexible means clamped against the opposite sides of the metal section and movable therewith to prevent distortion or twisting thereof, and a guide for said movable device.

16. The combination of a support, a former over which a section of metal may be bent, devices secured to the opposite ends of the section of metal to support the metal section in operative relation to the former, one of said securing devices being yieldingly mounted and one of said securing devices being movable, and means engaging the opposite sides of the metal section to prevent distortion or twisting thereof.

17. The combination of a support, a former over which a section of metal may be bent, devices secured to the opposite ends of the section of metal to support one longitudinal edge of the metal section in operative relation to the former, one of said devices being adjustable and one of said devices being movable in the plane of the metal section, and means engaging the opposite faces of the metal section to prevent distortion or twisting thereof.

18. The combination of a support, a former over which a section of metal may be bent, devices, one of which is movable, secured to the opposite ends of the section of metal to support the metal section in operative relation to the former, one of said devices being yieldingly mounted and the other device being adjustably mounted, and means

engaging the opposite sides of the metal section to prevent distortion or twisting thereof.

19. In apparatus for bending a section of metal, the combination of a support, a former on the support, and a plurality of devices engaging the metal section from end to end and the support, one of the outermost devices being guided on said support and movable to bend the metal section over the former and the intermediate devices being movable on said support with the metal section as it is bent and operating against the opposite sides thereof to prevent its twisting or distortion.

15 20. The combination of a support, a former over which a section of metal may be bent, devices secured to the opposite ends of the metal section for holding it in operative relation to the former, and means slidably mounted on the support and engaging the metal section between said devices.

20 21. The combination of a support, a former over which a section of metal may be

bent, devices secured to the opposite ends of the metal section for holding it in operative relation to the former, means slidably mounted on the support and engaging the metal section between said devices, and means for supporting the former above the support to permit the slidably mounted means to move therebeneath.

22. The combination of a support, a former over which a section of metal may be bent, a device for holding one end of the metal section, a movable device for holding the opposite end of the metal section, and means engaging the metal section between said devices for preventing distortion of the metal section, said means having sliding engagement with said support.

In testimony whereof, I hereunto set my hand this 15th day of December, 1910.

CARL M. YODER.

In presence of:—

GEO. S. COLE,
Wm. M. MONROE.
